[57] **CLAIM**

The ornamental design for a steering stabilizer, as shown and described.

DESCRIPTION

FIG. 1 is a top and left front perspective view of a steering stabilizer showing my new design;

FIG. 2 is a front elevational view of the left side thereof, the right side having been omitted for ease of illustration;

FIG. 3 is a rear elevational view of FIG. 2;

FIG. 4 is a top plan view of FIG. 2;

FIG. 5 is a bottom plan view of FIG. 2;

FIG. 6 is a right side elevational view of FIG. 1, the vertical is shown broken away for ease of illustration; and,

FIG. 7 is a left side elevational view of FIG. 1, the vertical is shown broken away for ease of illustration.

The broken line showing of a snowmobile front suspension is for illustrative purposes only and forms no part of the claimed design.
